UNITED STATES PATENT OFFICE.

THOMAS E. POPE, OF SAYRE, OKLAHOMA.

IRONING-TABLE.

1,098,682.

Specification of Letters Patent. Patented June 2, 1914.

Application filed April 3, 1912, Serial No. 688,276. Renewed April 15, 1914. Serial No. 632,103.

To all whom it may concern:

Be it known that I, THOMAS E. POPE, a citizen of the United States, residing at Sayre, in the county of Beckham and State of Oklahoma, have invented new and useful Improvements in Ironing-Tables, of which the following is a specification.

This invention relates to new and useful improvements in an ironing board device, and the primary object of this invention is to provide a support for an ironing board whereby the same may be folded upon the board in a compact form, thereby taking up but a limited amount of space when the same is not in use.

Another object of the invention is to provide foldable supports or props that will afford a broad base for the table.

Other objects of this invention will appear hereinafter as the description continues.

With the above and other objects in view this invention consists of the novel construction, combination, formation and arrangement of parts as will be hereinafter more fully described, claimed and particularly pointed out in the appended drawings, in which:

Figure 1 is a side elevation of an improved ironing board when in use, showing the cloth holder in a raised position in dotted lines, Fig. 2 is a rear elevation of the same, Fig. 3 is a front elevation of the same with the sleeve board removed, Fig. 4 is a bottom plan view illustrating how the means of support may be folded upon the bottom of the ironing board, and Fig. 5 is a cross section taken on the line 5—5 of Fig. 4.

Referring now more particularly to the drawings, wherein like parts are illustrated by like reference numerals throughout the several views, the numeral 10 indicates an ordinary ironing board which is preferably squared at its rear end and tapers to a rounded front end portion. A sleeve board 11 is adapted to be detachably secured to the upper face of the ironing board and the means for detachably securing this sleeve board to the ironing board consists of a depending arm 12 which is bent at its lower extremity into a hook portion which is adapted to engage a staple 13 placed approximately at the center of the ironing board and at the rear thereof. A block 14 is secured to the under face of the sleeve board to provide means for supporting the

forward end of the sleeve board. It is obvious from this construction that a sleeve of a garment may be easily and readily drawn over the end of the sleeve board, thereby facilitating the ironing of the same and the arm 12 will prevent the sleeve board from tilting, whereas the block 14 will form a support for the sleeve board and hold the same in a spaced relation from the ironing board proper.

When ironing boards of this character are in use they generally are provided with a cloth which will protect the articles which are to be ironed from the dirt and wear of the board and to provide means whereby this cloth may be held upon the face of the ironing board I provide a frame which is adapted to extend around the edges of the ironing board and which will engage the cloth and clamp the same tightly around the edge of the board. This frame consists of two side members 15 which are adapted to fit along the sides of the board and are joined or connected at their forward ends in any suitable manner by a flexible metal strap 16 which is curved to conform to the forward or curved end of the ironing-board. Each of the side members 15 is provided with a plate 16^a having a slot 16^b adapted to engage set screws or pins 17 and 18 on opposite sides of the ironing-board, whereby the frame may be detachably secured to the said pins or set screws. In order to permit the frame to accommodate cloth or coverings of different thicknesses and be drawn tightly around the board, the set screw or pin 18 is removable and a plurality of openings 19 are provided in one side edge of the board to removably receive the pin 18. A plurality of lugs 20 are formed on the under face of the board, as best shown in Fig. 4 of the drawings, which lugs provide suitable rests or means of support for the side members 15. These lugs 20 are fastened at one end to the under side of the ironing-board and the opposite ends extend beyond the board to support the clamping frame for the cloth.

To provide a suitable means of support for this board when in use I provide on the under face and rear extremity of the board depending lugs 21 which have journaled therein an axle 22, this axle having secured thereto a diagonally extending support 23. The lower end of this support 23 is beveled as at 24 so that the same may rest upon the

floor. To provide means to maintain this support in proper position when unfolded I provide a second support 25. This second support 25 is also secured at one end to an 5 axle 26 which is journaled in lugs formed on the under side of the board 10. This support 25 is of less length than the before mentioned support and has pivoted thereto a pair of supporting legs 28. To prevent 10 these legs from spreading I pivotally mount in the lower extremity of this member 25 arms 29 which have off-set portions formed at the outer extremities thereof which are adapted to slide within elongated slots 30 15 formed within the members 28. Each of these slots is provided at the upper extremity with a recess in which the extremities of the arms 29 may rest when the legs are in outward position.

20 It is apparent from Fig. 4 of the drawings that the diagonally extending support 23 is connected to the axle 22 at one side of the center of the ironing board and that the support 25 is pivotally secured adjacent the opposite side of the center of the ironing board. This will permit the two supporting members to be folded upon the bottom of the board when the lower supporting members 28 are in a folded position, as shown in Fig. 30 4 of the drawings, and to provide means to prevent the supporting members from moving out of proper position when unfolded I provide an extending lug 31 which is secured to the member 25 against which bears the 35 upper side of the supporting member 23. Extending from the side of the member 23 is a lug 32. These lugs 31 and 32 will prevent the supporting members from spreading from their proper relative position in an 40 outward longitudinal direction when the device is unfolded and to prevent the same from moving accidentally in an opposite direction I provide upon the supporting member 23 a hook 33 which is adapted to engage 45 a staple provided upon one face of the supporting member 25, as shown.

As one means to prevent movement of the support member 23, and supporting member 25, a bracket 34 may be employed and fastened to the under face of the board 10, as shown. This bracket is provided with side lugs 35 distanced from each other, both lugs being formed adjacent the ends of the bracket and extending downwardly therefrom. When folded, as seen in Fig. 5, the support 23 and supporting member 25 are received by the bracket intermediate the lugs 35. Lateral movement of the support member 23 and supporting member 25 when thus 50 folded, would be prevented, inasmuch as the folded members would be held against such movement by their abutment against the lugs 35.

It is obvious from the foregoing description, taken in connection with the accom-

panying drawings, that I have constructed an ironing board device which will be cheap to manufacture, durable and efficient in use and which will perform all the necessary requirements of such a device and it is to be further understood that minor details of construction may be resorted to that come within the scope of the appended claims without sacrificing any of the features of this invention. 75

Having described my invention, what I claim as new and desire to secure by Letters Patent, is:-

1. In a device of the class described, a board, a plurality of foldable supports pivoted thereto and arranged to extend in crossed relation in unfolded position, means to limit the movement of said supports relatively, and a plurality of laterally movable legs pivoted to one of said supports, so that 80 one of said legs may be moved across the plane of movement of one of said supports and returned to folded position so as to offer no interference to the folding of said latter support. 85

2. In a device of the class described, a board, a plurality of relatively close foldable supports pivoted thereto and arranged to extend in crossed relation in unfolded position, a projecting member on one of said supports to engage the other support to limit the movement of said supports relatively, and a plurality of laterally movable legs pivoted to one of said supports below said projecting member, so that one of said legs may 95 be moved across the plane of movement of one of said supports and returned to folded position so as to offer no interference to the folding of said latter support. 100

3. In a device of the class described, a board, a plurality of foldable supports pivoted thereto and arranged to extend in crossed relation in unfolded position, means to limit the movement of said supports relatively, a plurality of laterally movable legs pivoted to one of said supports, so that one 105 of said legs may be moved across the plane of movement of one of said supports and returned to folded position so as to offer no interference to the folding of said latter support, and means to limit the lateral unfolding movement of said legs. 110

4. In a device of the class described, a board, a support, a support member foldable relatively thereto, both said support 120 and member pivoted to said board and arranged to extend in crossed relation in unfolded position, means to limit the movement of said support and member relatively, a plurality of laterally movable legs pivoted to said support member, so that one of said legs may be moved across the plane of movement of said support and returned to folded position so as 125 not to offer interference to the folding of 130

said support, arms pivoted to said support member, said legs provided with elongated slots, and said arms extending into said slots, whereby means are provided to limit the movement of said legs to unfolded position.

5. In a device of the class described, a board, a support, a support member foldable relatively thereto, both said support and member pivoted to said board and arranged to extend in crossed relation in unfolded position, a projection from one of said parts to engage the other part, a plurality of laterally movable legs pivoted to said support member, so that one of said legs may be

15 moved across the plane of movement of said support and returned to folded position so as not to offer interference to the folding of said support, arms pivoted to said support member, said legs provided with elongated slots, and said arms extending into said slots, 20 whereby means are provided to limit the movement of said legs to unfolded position, and means to prevent the spreading of said legs while in folded position.
